UNITED STATES PATENT OFFICE.

FRANZ A. BOEDTCHER, OF BERGENFIELD, NEW JERSEY.

ELECTRIC SWITCH.

1,333,241.

Specification of Letters Patent. Patented Mar. 9, 1920.

Original application filed February 21, 1914, Serial No. 820,188. Divided and this application filed December 16, 1915. Serial No. 67,181.

To all whom it may concern:

Be it known that I, FRANZ A. BOEDTCHER, a citizen of the United States, residing at Bergenfield, county of Bergen, and State 5 of New Jersey, have invented certain new and useful Improvements in Electric Switches, of which the following is a specification.

This invention relates to improvements in 10 electric switches, and the object of the invention is to produce a switch which may control one or more electric circuits and which will be extremely simple in construction, durable and efficient in operation, and 15 not apt to get out of order.

The switch of the present invention is particularly applicable for use in elevator signaling and controlling systems, and its employment in this environment is dis- 20 closed in my allowed application Serial No. 820,188, filed February 21, 1914, of which the present application forms a division.

Speaking generally, the invention embodies one or more contacts, in operative re- 25 lation to which is pivotally mounted a movable member normally out of engagement with the contact or contacts, but adapted, when operated upon by suitable mechanism, to make connection with one of said contacts and thus close the circuit, preferably momentarily.

In one of its preferred practical forms, the invention embodies a pair of spaced contacts which are either resilient or resiliently 35 mounted, and between these contacts extends an arm which is mounted for pivotal movement, but normally held out of engagement with either of the contacts by a resilient member which serves to carry current 40 from the main. With the movable member co-operates a trip which is automatically operated by the movements of the device with which the switch is associated whereby the trip, in engaging with the movable 45 member forces the same into engagement with one or the other of the contacts and completes the circuit from the main through the wiring associated with the contact engaged. When moving in the 50 opposite direction, the trip shifts the movable member into engagement with the other contact and switches the circuit from the main through the wiring with which said contact is associated. This is 55 the construction preferably employed in

controlling two circuits. If only one circuit is required, only one contact would be used.

Features of the invention, other than those specified, will be apparent from the hereinafter detailed description taken in 60 conjunction with the accompanying drawings.

In the accompanying drawings, I have illustrated one practical embodiment of the invention, but the construction shown there- 65 in is to be understood as illustrative, only, and not as defining the limits of the invention.

Figure 1 is a longitudinal vertical section through a casing disclosing in side elevation 70 one embodiment of the invention, certain parts of an elevator system being shown associated therewith.

Fig. 2 is a section through Fig. 1 approxi- 75 mately on line 2—2, certain parts being broken away, and

Fig. 3 is a section taken on line 3—3 of Fig. 1.

As heretofore stated, the invention is particularly adapted for use with elevator sig- 80 naling or controlling systems, and, accordingly, for the purpose of illustration, the drawings show the invention in this environment. In elevator systems of the type, e. g., shown in my copending application 85 referred to, switches are necessary for causing the proper operation of the annunciators in the elevator cars. That is to say, when a button is pushed by a passenger at a floor, the annunciator in one or more of 90 the cars will be operated to show what floor the passenger is on. When the elevator is ascending, the signals given by the persons desiring to go up will be recorded on the annunciator, and, when the elevator is de- 95 scending, the signals of those persons desiring to go down will be exhibited. Two circuits are, therefore, necessary, which circuits correspond to the up and down direc- 100 tions of the elevator. The present invention is shown in the drawings as associated with such a system, although it will, of course, be understood that said invention is not limited to this specific showing or to the em- 105 ployment of a pair of circuits. Moreover, the invention might readily be used in controlling circuits operated by elevator doors, in which case the switch of this invention would be employed in lieu of those now used.

Referring to the drawings, 1 indicates the 110

usual rod or cable of an elevator system wherein a "snake" is employed for operating the signals. The cable is connected with the usual indicating members or pointers at each floor for advising a prospective passenger of the movements or positions of each of the cars. The mechanism for only one car is shown, and the description will, therefore, be limited to such singular showing, it being manifest that, with a plurality of cars, mere duplication would be necessary. When the car referred to ascends, rod 1 moves upwardly slightly, and, as it so moves, a clamp 2, which is fixedly secured thereto in any desirable way, is correspondingly moved. Clamp 2 is connected by a link 4 to an arc-shaped member 3 fixedly secured to a shaft 7. Rod 1 is thus, when ascending, adapted to raise member 3 and rotate shaft 7 in a clockwise direction, whereas, when rod 1 descends, the weight of member 3 is sufficient to reverse the rotation of shaft 7 to its initial position. To arc-shaped member 3 may be connected an arm 5 adapted to operate, through a rod 6, an indicating clock or pointer of any desired kind for designating the direction of travel and position of the elevator.

It is on shaft 7 that the means for operating the switch of the present invention is mounted, and the means shown is in the form of three radial arms 8' and 8'', which are secured to the shaft and are moved in synchronism therewith. The switch mechanism forming the present invention will now be described.

The switch mechanism shown in the drawings is in the form adapted to control a plurality of circuits, *e. g.*, the up and down circuits for three floors of a building in an elevator signaling system. In this embodiment, a block 14, preferably of insulation material is provided on the opposite faces of which block are positioned complementary pairs of contacts, shown as brushes 15-18, 16-19 and 17-20. These pairs of brushes are spaced apart and are loosely secured at their rear ends to block 14 by means of screws 21. Intermediate the ends of each brush and passing loosely through apertures therein are screws 22 which are threaded into block 14, and around which are coiled springs 23. These springs normally impel the brushes of the respective pairs toward one another and into engagement with the faces of block 14. To each of the brushes is secured a wire 25 for electrically connecting the brush to the circuit to which it corresponds, and the brushes of each pair, as well as the brushes of all the pairs, are insulated from one another by virtue of the insulating character of block 14.

Mounted upon the edges of block 14, and extending beyond the end thereof, are side plates 32 33 which carry at their ends a block of insulation 28', the function of

which will be hereinafter explained, and intermediate blocks 28' and 14, a shaft 13' extends between said side plates. On shaft 13', and insulated from one another, is a plurality of T-pieces or movable members 70 11, 12 and 13, equal in number to the number of pairs of brushes, and placed in juxtaposition upon the shaft relative to said brushes. Fixed upon block 14 is a plurality of leaf-springs 30 which reach over the 75 brushes 15, 16 and 17 and engage at their free ends with the T-pieces adjacent the points of pivoting thereof. The tension of leaf-spring 30 is sufficient to normally maintain the arms of the T-pieces which extend 80 between the free ends of the brushes in positions normally intermediate the brushes of each pair and out of contact with either, each spring 30 being provided with a foot 31 resting on its T-piece, which foot facilitates the centralizing of the T-piece. Each 35 T-piece, or at least a portion thereof, and the springs 30 are of conductive material, and each spring has a binding post to which is secured a wire 25' which is in electrical 90 communication with the main adapted to supply either brush of each pair.

T-pieces 12, 11 and 13 each have a depending portion 10, 10' and 10'', respectively, which are normally in the path of arms 8', 95 8 and 8'', respectively, mounted on shaft 7. Arms 8, etc., are preferably of insulation material, or at least a portion of them insulated when the T-pieces are of conductive material. Thus, when shaft 7 is rotated by 100 the means hereinbefore described, the arms will come into engagement with the depending portions of their corresponding T-pieces and tilt said T-pieces into engagement with either of the corresponding brushes in accordance with the direction of movement of shaft 7. *E. g.*, if shaft 7 is moving in a clockwise direction, arm 8, with its insulating portion 9, will strike the depending portion 10 of T-piece 12 and rock said T-piece on shaft 13' into engagement with the brush 19, thereby completing the circuit from wire 25', through leaf-spring 30, T-piece 12, and brush 19, to wire 25. Each of the remaining arms 8' and 8'' will operate 105 in a similar manner upon their respective T-pieces when shaft 7 is turned in a clockwise direction. However, when the shaft is turned in a counter-clockwise direction, the engagement of arm 8 with the depending portion 12 of its T-piece will rock said T-piece into engagement with brush 16 and establish a current from wire 25' through spring 30, T-piece 12, and contact brush 16, to the other wire 25. The other arms 8' and 110 8'' will operate in a similar manner, when the shaft is rotated in a counter-clockwise direction.

It will be noted that, as shaft 7 turns, arms 8, etc., are brought into engagement 115

with the depending portions of their T-pieces, tilt the T-pieces into engagement with the brushes, and, as the shaft continues to rotate, said arms pass beyond the T-pieces and allow spring 30 to bring said T-pieces back to their normal positions. As the arms travel in synchronism with the elevator car, their movement is generally at such speed that the tilting of the T-pieces to make the circuit is usually only momentary. That is to say, the circuits are generally broken, through the releasing of the T-pieces by the associated arm, immediately after the circuit is completed, so that the "make" is but momentary. Such a momentary current is all that is usually required in elevator circuit control, and I recommend its employment because of its economy in current consumption. It is to preclude undue straining of the brushes during the maximum angle of tilt of the T-pieces that springs 23 are provided, it being manifest that, if said brushes were rigid, undue strain might be placed upon the mechanism during the period referred to. However, if the brushes are made resilient, or in leaf-spring form, screws 22 and springs 23 may be omitted.

In the form of the invention shown, the switch mechanism is positioned within a casing 26, and block 14 is pivotally secured, as at 27, to the wall of the casing. Through block 28', at the other end of the switch mechanism, extends a post 28 which is secured to the wall of the casing, and around said post is coiled a spring 29. Said spring is on the opposite side of the switch mechanism from that side on which shaft 7 is located, and, accordingly, the pivoting of the switch mechanism, and the cushioning of the same by means of spring 29, obviate any jar or vibration which, perhaps, might otherwise result from the quick operation of the T-pieces by arms 8, 8' and 8''.

The foregoing description sets forth in detail one specific embodiment of this invention, and its manner of use and operation. However, it is to be understood that the present invention is not limited to the construction or use illustrated and described. E. g., three pairs of switches are shown, and three arms are shown on shaft 7 for controlling said switches. Manifestly, only one pair of switches and one arm might be employed. Moreover, if only one circuit were to be used, only one brush would be necessary, one of the brushes of the pair being dispensed with. Furthermore, in utilizing the switch of the present invention as a door switch, or in any other environment, the pivoting of block 14, and the cushioning thereof by means such as spring 29, are unessential, as well as the particular means for operating the arms mounted on the shaft. These arms might be the catch of a door-

lock or a projection on some moving part other than a shaft. The invention is, therefore, not restricted to the details of construction specified, but is to be understood to be as broadly novel as is commensurate with the appended claims.

Having thus fully described the invention, what I claim as new, and desire to secure by Letters Patent, is:

1. As a new article of manufacture, an electric switch embodying a plurality of spaced, insulated contact members with each of which is associated one lead of an electric circuit, swinging bars, insulated from each other, coöperating with said contact members and each of which bars is in electrical connection with the circuit of the corresponding contact member, said swinging bars being adapted to be individually swung to contact with their respective contact members for closing the circuits associated therewith, and resilient current carrying means for normally maintaining the swinging bars free from engagement with the contacts.

2. As a new article of manufacture, an electric switch embodying a pivotally mounted supporting bar formed of insulating material, cushioning means coöperating therewith, upper and lower contact members projecting therefrom, means for resiliently holding said contact members in operative position, and a pivotally mounted arm adapted, when actuated, to connect either of said contact members with a source of current, thereby completing the circuit of the respective contact members.

3. As a new article of manufacture, an electric switch embodying a supporting bar of insulation, a pair of contact members loosely mounted on opposite sides of said bar of insulation, springs arranged adjacent each of said contact members for resiliently holding them against said bar of insulation, said contact members projecting beyond said bar of insulation, a pivotally mounted contact bar arranged with one end between said first-mentioned contact members and designed to be swung to engage either of said contact members, and means for normally holding the contact bar out of engagement with the contact members, said means acting as an electrical conductor for completing the circuit when the swinging contact bar is in engagement with either of said first-mentioned contact members.

4. As a new article of manufacture, an electric switch embodying a pair of oppositely movable contacts insulated from each other, a swinging bar arranged with its end projecting between said contacts, an operating arm for actuating said swinging bar, a spring member for normally holding said swinging bar in a neutral position, and

- 4
- means for actuating said arm to bring the bar into engagement with either of said contacts.
5. As a new article of manufacture, an electric switch embodying a contact member, a swinging contact, means for actuating said swinging contact, means for supporting both of said contacts, and a resilient member for holding said supporting means normally in 10 a predetermined position relative to the actuating means, said resilient means being designed to cushion the switch mechanism when operated upon by the actuating means, and thereby relieve unusual strain on the 15 device.
6. As a new article of manufacture, an electric switch embodying a supporting member, an electrically connected contact thereon, an electrically connected swinging member also mounted on the supporting member, means for normally maintaining the swinging member free from engagement with the contact, means for actuating the swinging member to bring it into engagement with the contact, in combination with 20 means for cushioning the supporting member against the operations of the actuating means.
7. As a new article of manufacture, an 30 electric switch embodying a supporting member of insulating material, upper and lower contact members mounted thereon and projecting beyond the edge thereof, means for resiliently holding the contact members 35 in operative position, and a pivotally mounted arm adapted, when actuated, to connect either of said contact members with a source of electric current, and means for normally maintaining the pivotal arm in neutral position.
8. As a new article of manufacture, an electric switch embodying a supporting member, a pair of contacts loosely mounted on opposite sides thereof and insulated from one another, springs arranged adjacent each 45 of said contact members for forcing them toward one another, a pivotally mounted contact bar arranged with one end between the contact members and designed to be swung to engage either of said contact members, 50 and means for normally holding the contact bar out of engagement with the contact members.
9. As a new article of manufacture, an electric switch embodying a pair of spaced 55 movable contacts insulated from one another, a pivoted member arranged to project between said contacts, means for actuating the pivoted member, and a single leaf spring provided with a foot engaging with 60 the pivoted member on opposite sides of the pivot point of said member for normally holding the member in neutral position.
10. As a new article of manufacture, an electric switch embodying a supporting 65 member, a pair of spaced movable contacts mounted thereon and insulated from one another, a pivoted member mounted on the supporting member and arranged to project between said contacts, means for operating 70 said pivoted member to swing it into engagement with either of said contacts, and a single leaf spring mounted on the supporting member and engaging with the pivoted member at opposite sides of the pivot thereof 75 for normally maintaining the pivoted member in neutral position.

In testimony whereof I have signed my name to this specification.

FRANZ A. BOEDTCHER.
